(57) **CLAIM**

The ornamental design for a wheeled holder for carpet cleaning nozzle, as shown and described.

DESCRIPTION

FIG. 1 is a perspective view of the wheeled holder for carpet nozzle with the nozzle shown in broken lines.

FIG. 2 is a top view.

FIG. 3 is a side view, the other side being a mirror image.

FIG. 4 is a bottom view; and,

FIG. 5 is a front view.

The broken line showing of the nozzle is for illustrative purposes only and forms no part of the claimed design.
